UNITED STATES PATENT OFFICE.

MAURICE M. MINTER, OF ALBANY, GEORGIA, ASSIGNOR OF ONE-HALF TO PAUL JOE BROWN, OF ALBANY, GEORGIA.

KILN.

1,272,495.

Specification of Letters Patent. Patented July 16, 1918.

Application filed April 10, 1918. Serial No. 227,651.

To all whom it may concern:

Be it known that I, MAURICE M. MINTER, a citizen of the United States, and a resident of Albany, in the county of Dougherty and State of Georgia, have invented a new and useful Improvement in Kilns, of which the following is a specification.

My present invention relates generally to kilns and more particularly to a kiln system involving a circuit of successively operating kilns arranged in a series, my primary object being the provision of a system which may be economically operated, which will be continuous in its action, avoid shut-downs, permit of the burning of different materials in successive kilns, and provide for cutting out of operation any one or more kilns undergoing repair without affecting the action of the others or the system as a whole.

With these general objects in mind, the more specific objects of my invention as well as the advantages incident thereto, involved in part in the particular construction of the kilns themselves as well as the connections extending therefrom and therebetween, will be better understood and more thoroughly appreciated from the following description in which reference is had to the accompanying drawings, forming a part of this specification, and in which

Figure 1 is a plan view more or less diagrammatic, of the complete system, certain of the kilns in action being shown in horizontal section,

Fig. 2 is a vertical longitudinal section through the system,

Fig. 3 is a diagram of the underground flues extending from and between the kilns,

Fig. 4 is a horizontal section through a portion of one of the kilns on an enlarged scale,

Fig. 5 is a vertical section through a portion of one of the kilns in course of burning, illustrating the injecting device for heated products,

Fig. 6 is a side view of one of the segmental flues,

Figs. 7, 8 and 9 are partial vertical sections taken respectively on lines 7—7, 8—8 and 9—9 of Fig. 6,

Figs. 10 and 11 are respectively a plan and a vertical longitudinal section, the latter enlarged, through one of the brake members,

Fig. 12 is a vertical section through the heat injecting fan and its support,

Fig. 13 is a vertical transverse section taken substantially on the line 13—13 of Fig. 12.

Referring now to these figures and particularly to Figs. 1 to 3 inclusive, my invention proposes a system consisting of a continuous series of kilns 15, each of which has an annular wall 16 and the usual shaped crown 17 surmounting the wall 16, the latter being provided with a circular series of openings located adjacent the ground level and indicated at 18. Inwardly beyond each of the openings 18 which latter form the fire doors, are the usual vertically disposed baffles 19 which cause the products to take an upward course as indicated in Fig. 5. The series of continuously operating kilns 15 are preferably arranged in parallel lines, or adjacent lines to provide for the convenient extension between these lines of an induction flue 20, closed at one end and having an induction fan 21 at its opposite end as seen in Fig. 1, this flue being connected to the several kilns of the series by branch induction flues 22, having dampers 23 therein adjacent to the flue 20 so that any one or more of the series of kilns may be cut off in respect to the action of the induction fan 21.

The entire system consisting of the series of kilns 15 is surrounded by a continuous flue 24 which I will hereafter term the circuit flue, this flue being connected to the several kilns by branch circuit flues 25, each having a damper 26 therein adjacent to the main circuit flue 24 in order that any one or more of the kilns may be cut out of the system in case of necessary repairs and the intended action of the system as a whole permitted without interruption.

Each of the kilns 15 has a central outlet opening 27 in its base communicating with one end of a connecting flue 28 leading toward one side of the next adjacent kiln in advance thereof in the series, each of these connecting flues 28 having spaced dampers 29 and 30 located between the kilns of the series and therefore readily accessible.

Each of the kilns of the series is capable of being acted upon by the induction fan 21 by virtue of the fact that its particular branch induction flue 22 communicates with

its outlet flue 28 at a point between the respective kiln and its nearest outlet damper 29, and each of the kilns is capable of connection with the circuit flue 24 by virtue of 5 the fact that the respective branch circuit flue 26 communicates with its outlet flue 28 at a point between the two dampers 29 and 30, all of which may be plainly seen by reference to Fig. 1 and more thoroughly appreciated by virtue of the diagram Fig. 2.

In the action of the apparatus a step-by-step advance throughout the series of kilns is maintained as each kiln is fired, the previously fired kiln being cooled, the next in 15 advance fired, the next preheated and the next water-smoked or dried, so that a continuous operation of this nature is carried on at all times, one complete operation being indicated in Fig. 1, where the kiln A is cooling, the kiln B is firing, the kiln C is pre-heating, and the kiln D is water-smoking, and each of the kilns B, C and D are utilizing 20 for their respective purposes a certain proportion of the heat products of the kiln A which is cooling.

For the above purpose the doors 18 of the kiln A are open, cool external atmosphere being drawn inwardly through these doors in the same rate that the internal heat products are removed through the outlet flue 28 thereof. With the damper 29 at the right of kiln A open it is obvious that a portion of the heat products from the kiln A will pass through the next adjacent branch circuit flue 25, the damper 26 of which is open so that these products may pass into the main circuit flue 24, past the kiln B which is firing and, having divided and regulated proportions thereof passed into the preheating kiln C and the water-smoking kiln D, the damper 29 of kiln D being closed and the damper 30 open. Both the preheating kiln C and the water-smoking kiln D are at this time under the direct action of the induction 40 fan 21 by virtue of the open dampers 23 of their branch induction flues 22.

During this action the dampers 23 of the branch induction flues 22 of the cooling kiln A and firing kiln B are closed, so that with 50 the damper 30 between kilns A and B closed and the damper 29 between kilns B and C partly open, the firing kiln B is indirectly subject to the influence of the induction fan through the kiln C while the cooling kiln 55 A is indirectly subject thereto through the kilns C and D and the circuit flue 24 with its branches 25.

It will be noted by reference to Figs. 4 and 5 that each of the outlet flues 28 may 60 communicate with the atmosphere through vertical opening 31 and 32 upon respectively opposite sides of each damper 30, the outer end of each of these outlet flues 28 forming a separate box with the damper 30 closed as 65 seen in Fig. 5 into which heated products

from the cooling kiln may be injected under pressure by virtue of means communicating with the two openings 31 and 32.

Communicating at their open ends 33 with the outer ends of each of the outlet flues 28 70 and surrounding the major portions of each of the kilns 15 are a pair of segmental flues 34 having spaced side openings 35 as particularly seen by reference to Figs. 4 to 9 inclusive, equaling in number the doors 18 of 75 the kilns, these segmental flues being connected by pipes 36 extending from their openings 35 upwardly and inwardly at angles as seen particularly in Fig. 5, within the lower portions of the doors or fire openings 18 so as to provide for the disposal of 80 a grate generally seen at 37 in Fig. 5 over the outlet end of each pipe 36.

As above stated, the segmental flues 34 communicate at their open ends 33 with the upper ends of the outlet flues 28, the opposite ends of these segmental flues being closed as seen at 38 in Fig. 6, whereby the heat products passing into these flues through their open ends 33 will divide and pass upwardly into the kilns through the doors 18 and through the pipes 36 opposite and leading to these doors. In order to equalize the heat around the kilns these pipes 36 commencing from the intake ends of the segmental flues 34 are plugged by plugs 39 or otherwise partially closed, the plugs gradually reducing in size throughout each flue 34 so as to thus graduate the amount of heat passing through the pipes 36 of the series of 90 each kiln, and in this way provide for a uniform intake of heat products around the entire kiln and an even temperature therein.

It is obvious that with the dampers 30 open at the left of each of the preheating 105 and water-smoking kilns C and D of Fig. 1, these kilns will receive in the graduated manner above described, portions of the heat products of the cooling kiln A, through the main circuit flue 24 and the branch circuit 110 flues 25, under the influence of the induced draft from the fan 21. Thus kiln C will receive all the products of combustion from kiln B.

It is equally obvious that from the above 115 the kiln B which is firing is under the influence of the induction fan 21 but does not receive heat products from the cooling kiln A, owing to the closed damper 30 at its left, except by the action of other parts which I 120 will now describe.

Referring particularly to Figs. 5, 12 and 13 my invention proposes a portable fan 40, within a casing 41, communicating at its lower portion with a tubular extension 42 125 in which a connecting pipe 43 is telescoped at its upper end, the lower portion of said pipe 43 being adapted to extend into the flue opening 32 before described and having a surrounding flange 44 which engages the 130

surface of the ground as particularly seen in Fig. 12.

At one side the casing 41 of the fan has an opening 45, through which the heat products are drawn with any desired proportion of cool air as presently described, so that these heat products may be forced downwardly through the extension 42 and pipe 43 and through opening 32 into the closed 10 outer end of the flue 28 and from thence into the segmental flues 34 of the kiln B.

It is obvious that the fan 40 must be able to resist very high temperatures as it takes in the products from the cooling kiln at a 15 very highly heated point, and for this purpose its shaft 46 as seen in Figs. 12 and 13 is of comparatively large diameter and has a lengthy continuously oiled bearing within a casing 47 having an inner oil chamber 48 and a water chamber 49 around the oil chamber. The bearing 50 of the shaft 46 is continuously supplied with lubricant from the chamber 48 and for this purpose is slotted 20 as seen at 51 in Fig. 13 to receive freely 25 movable oiling rings 52 whose lower portions extend into the oil supply of the chamber 48, the oil feed or intake of the chamber 48 being indicated at 53 in Fig. 12.

The lower portion of the water chamber 30 49 is divided by an upright partition 54 through which a pipe 55 is extended opening at one end upon one side of the said partition and communicating at its opposite end with a pump 56 located and discharging upon 35 the opposite side of the partition, the shaft 57 of said pump being connected by a belt 58 with the shaft 46 of the fan which latter is driven by any suitable means, as for instance an electric motor 59 as seen in Fig. 12.

40 The fan just described as well as its driving motor and bearing are mounted upon a wheeled frame 60, the wheels of which appear at 61, so as to render the same portable and permit of its movement from one kiln to 45 the other during the progressive action of the series. Thus when kiln B has been fired for the required length of time, the fan is moved to the openings 31 and 32 at the left of the kiln C, at which time kiln B will be 50 cooling, kiln C firing, kiln D preheating and kiln E water-smoking or drying, it being understood that the openings 31 and 32 of the outlet flues of those kilns which are either cooling, preheating or water-smoking 55 are closed by suitable covers.

Opposite the intake openings 45 of the fan 40 in action is disposed the upper angular adjacent end 62 of a tubular upright 63, the lower end of which is adjustably telescoped upon a flanged pipe 64 adapted to extend into the opening 31 as seen particularly in Fig. 5, an adjusting ring 65 being telescoped upon the angular upper end 62 and being movable toward and away 60 from the fan intake opening 45 to control

the relative proportions of the heat products drawn by the action of the fan upwardly through the tubular upright 63 from the outlet flue 28 and the atmosphere taken into the fan along with said heat products 70 around the ring 65 as indicated by the arrows in Fig. 12.

To assist in the proper control of the heat passing through the fan, the latter has a thermometer 66 at one side as seen in Fig. 5 75 and the tubular upright 63 may have a side control damper 67 as seen in the same figure.

In the firing of each of the kilns hollow grates 37, before mentioned, are utilized over the outlet ends of the pipes 36 from the 80 segmental flues 34 in the manner seen in Fig. 5 and as these grates may frequently be handled while hot and are subjected to very high temperatures by virtue of the heated products passing upwardly therethrough 85 from the pipes 36, it is essential that they be so formed as to successfully resist these influences and minimize breakage. To this end I preferably construct the grate 37 of oval form to give strength, with one inclined 90 wall 68 at one end, and utilize plastic material in successive layers, each layer being of different constituents in view of the different spacing of these layers from the point of greatest heat and the layers having different 95 coefficients of expansion. This structure is to be broadly seen in Fig. 11 and it will be noted that the upper and lower or outer and inner layers 69 and 70 are relatively thin as compared to that of the central layer 71, 100 the latter being of a width or thickness approximately equal to the combined thicknesses of the outer and inner layers 69 and 70.

It is of course obvious from the foregoing description, that the dampers 23 of the 105 branch induction flues 22 of those kilns entirely out of action, and in addition to those cooling and firing, are closed, and that to prevent waste the circuit flue 24 has dampers 72 which are seen in Figs. 1 and 3 and which 110 are located to the left or at the rear of the several branch circuit flues 25 in respect to the progression of the action in the series of kilns whereby those portions of the circuit flue beyond the kilns immediately in action 115 may be cut off.

From the foregoing it will be understood that any particular kiln or kilns may be cut out of the circuit or series where repairs are necessary, without preventing operation 120 of the others or interfering with such operation and that my invention provides for complete utilization of all heat products which might otherwise be wasted and will provide for much more economical operation than has heretofore been possible.

Attention is, however, called particularly to the fact that the waste heat from kiln A is used in kiln B partially through fan (Fig. 12) in kiln C in conjunction with waste heat 130

from burning kiln B through partially opened damper 29 between B and C. At the junction point of flues 25 and 28 a portion of waste heat from kiln A is added to the 5 full volume of heat from burning kiln B and both volumes are passed into and through kiln C. But no part of the gases or products of combustion ever pass from B through C to D (watersmoking). All the 10 volume is passed through flue 22 to main induction flue by closed damper 29 between kilns C and D.

Kiln D only receives waste heat from cooling kiln A for removal of moisture.

15 Kiln B (firing) is connected to induction flue through kiln C (preheating) only.

Kiln A (cooling) is connected to induction flue through kiln D, kiln C and through kiln C to B.

20 The induction fan is connected to the draft volume of all four kilns all the time, as the function of the hot air fan is only to force hot air through the grates of the burning kiln B after which the induction 25 fan power is operative to carry the draft forward through kiln C (sealed) to outlet flue 22. The use of waste heat from kiln A at three points is necessary to utilize the great volume of heat contained therein when 30 the burning is complete, but is really secondary in importance to the use of burning heat carried from kiln B to C during the burning period of kiln B.

The relative importance of the passage 35 of heat from kiln B through C will be understood when the short distance from A to B through the fan and from B to C through the flue are considered. From A to C and A to D are by circuitous routes.

40 Heat from kiln A is by-passed to kiln C and mixed with heat passing from kiln B to kiln C at the junction of flues between B and C.

At the beginning of actual firing of kiln 45 B the heat by-passed as described will be of higher temperature than the heat passing directly from burning kiln B to preheating kiln C. As the burn progresses in kiln B the heat discharged from it through flue to 50 kiln C will increase in temperature and the heat from kiln A by passed around kiln B and combined with heat from kiln B passing to kiln C will decrease in temperature.

When the heat by-passed from kiln A to 55 kiln C falls in temperature by reason of the cooling of kiln A below the temperature of gases passing from kiln B to C, the damper 26 is closed and all the heat diverted to and through watersmoking kiln D, except the 60 part used by the fan for preheating air for combustion in kiln B. This will have utilized the main volume of waste heat from kiln A at three points and after the temperature has fallen 800 to 1000 degrees Fahrenheit in kiln A the volume of heat passing to

kiln D will be increased by closure of damper 26 without much increase of temperature of volume entering kiln D.

It is furthermore obvious, it is believed, that my invention will permit of quicker 70 more effective action and that in view of the uniform distribution of the heat products of each kiln, I am enabled to burn various materials in successive kilns, such as for instance brick, hollow blocks, tubes, pipes, and 75 in fact various other burnt clay products, including material that seums and discolors by direct firing, as watersmoking is done with clean heat containing no sulfur or carbonaceous matter.

80 I claim:—

1. The combination of a series of kilns, an induction flue having draft inducing means, damper controlled connections between the said flue and the several kilns, a 85 circuit flue around the series of kilns, damper controlled connections between the said circuit flue and the several kilns, and damper controlled connections between the several kilns of the series.

2. A series of progressively operating 90 kilns, each of which has an outlet flue extending to the next adjacent kiln in advance thereof, an induction flue having draft inducing means, damper controlled connections between the said flues and each of the 95 kilns, a circuit flue around the series of kilns, and damper controlled connections between said circuit flue and the said kilns, for the purpose described.

100 3. A series of progressively operating kilns, each of which has an outlet flue extending to the next adjacent kiln in advance thereof, an induction flue having draft inducing means, damper controlled 105 connections between the said flues and each of the kilns, a circuit flue around the series of kilns, and damper controlled connections between said circuit flue and the said kilns, the said connections between the induction 110 flue and the kilns leading into the said outlet flues of the kilns.

4. A series of progressively operating 115 kilns, each of which has an outlet flue extending to the next adjacent kiln in advance thereof, an induction flue having draft inducing means, damper controlled connections between the said flues and each of the kilns, a circuit flue around the series of kilns, and damper controlled connections between said circuit flue and the said kilns, the said damper controlled connections between the circuit flue and the kilns leading into the said outlet flues of the kilns.

120 5. A series of progressively operating 125 kilns having surrounding intake flues, and each provided with an outlet flue leading from its center to the intake flue of the next adjacent kiln in advance thereof, dampers controlling the said outlet flues, an induc-

tion flue, and damper controlled connections between the induction flue and the kilns leading into the outlet flues at points between the kilns and the said dampers of the 5 outlet flues.

6. A series of progressively operating kilns, each of which has intake flues around the sides thereof and an outlet flue leading from the center to the intake flues of the 10 next adjacent kiln in advance thereof, an induction flue having draft inducing means and having damper controlled connections with the several outlet flues of the kilns, a circuit flue surrounding the series of kilns, 15 and having damper controlled connections with the several outlet flues of the kilns, and dampers in the outlet flues located between the said connections of the induction and circuit flues.
7. A series of progressively operating kilns each having intake flues and an outlet flue leading therefrom to the intake flues of the next adjacent kiln in advance thereof, an induction flue having draft inducing 20 means and having damper controlled branches communicating between the same and the several kilns and leading to the said outlet flues, a circuit flue having damper controlled branches for the several kilns leading 25 to the outlet flues, the circuit branch of each kiln being farther removed therefrom than the induction branch of the respective kiln, and a damper located in each outlet flue between the induction branch and the circuit 30 branch thereof.
8. A series of kilns each having an annular series of door openings, intake flues extending around opposite sides of each of said kilns and having adjacent open ends, 35 pipes leading from the said intake flues into the door openings of the kilns, and an outlet flue leading from each of the kilns and communicating with the adjacent open ends of the intake flues of the next advanced kiln.
9. A plurality of progressively operating 40 kilns each having an annular series of door openings, segmental flues extending around opposite sides of said kilns, said flues having adjacent open ends and being closed at their 45 opposite ends, pipes leading from the said segmental flues into the several door openings of the kilns, and an outlet flue leading from each of the kilns and communicating with the adjacent open ends of the segmental flues of the next advanced kiln.
10. A plurality of progressively operating 50 kilns having annular series of door openings, intake flues around the kilns having intake pipes extending into the several door openings of the kilns, and an outlet flue leading from each of the kilns and communicating with the intake flue of the next advanced kiln.
11. A plurality of progressively operating 55 kilns having annular series of door open-

ings, intake flues around the kilns having intake pipes extending into the several door openings of the kilns, and an outlet flue leading from each of the kilns and communicating with the intake flue of the next advanced 70 kiln, the said intake pipes of the intake flues having progressively increasing intake ports starting from the point of communication of the respective outlet flue, for the purpose described.

12. A plurality of progressively operating kilns having annular series of door openings, intake flues around the kilns having intake pipes extending into the several door openings of the kilns, an outlet flue leading from each of the kilns and communicating with the intake flue of the next advanced kiln, said outlet flues having vertical openings at spaced points adjacent the intake flues and having dampers between the said openings, 80 and pressure creating means for establishing communication between the said openings when the damper is closed.

13. A plurality of progressively operating kilns having annular series of door openings, 90 intake flues around the kilns having intake pipes extending into the several door openings of the kilns, an outlet flue leading from each of the kilns and communicating with the intake flue of the next advanced kiln, 95 said outlet flues having vertical openings at spaced points adjacent the intake flues and having dampers between the said openings, and pressure creating means for establishing communication between the said openings 100 when the damper is closed, the said pressure creating means being movable from one kiln to another in the progressive operation, as described.

14. A plurality of progressively operating 105 kilns each having intake flues, and an outlet flue communicating at its outer end with the intake flues of the next adjacent kiln in advance thereof, each of said outlet flues having longitudinally spaced openings adjacent 110 the intake flues with which it communicates, dampers between the said openings of the outlet flues, and a portable fan having means of communication with the said openings, whereby to withdraw products of the outlet 115 flues at one side of the dampers and introduce the same under pressure within the intake flues at the opposite sides of the dampers.

15. A plurality of progressively operating 120 kilns each having intake flues, and an outlet flue communicating at its outer end with the intake flues of the next adjacent kiln in advance thereof, each of said outlet flues having longitudinally spaced openings adjacent 125 the intake flues with which it communicates, dampers between the said openings of the outlet flues, and a portable fan having means of communication with the said openings, whereby to withdraw products of the outlet 130 flues.

flues at one side of the dampers and introduce the same under pressure within the intake flues at the opposite sides of the dampers, said fan being portable from one kiln 5 to another throughout the series in action.

16. A plurality of progressively operating kilns having annular series of door openings and provided with inlet and outlet flues, grates for disposition in the said door

openings when the kiln is burning, and a 10 plurality of intake pipes leading from each of the intake flues into the door openings and opening therein below the said grates, as described.
